(57) CLAIM

The ornamental design for a hooded garment, as shown and described.

DESCRIPTION

1. Hooded garment
- 1.1 : Front right perspective
- 1.2 : Front elevation
- 1.3 : Back elevation
- 1.4 : Right side elevation
- 1.5 : Left side elevation
- 1.6 : Top
- 1.7 : Bottom

FIGS. 1.1-1.7 described in the legends below show the claimed design; the shading in the figures show contour, not surface ornamentation, and form no part of the claimed design.
